VARIABLE CONDENSER

Ralph E. Franklin and Earle Dayton Thorne,
Patchogue, N. Y., assignors to Radio Corpora-
tion of America, a corporation of Delaware

Application June 28, 1939, Serial No. 281,642

1 Claim. (Cl. 175—41.5)

This invention relates to a new and novel vernier variable condenser.

An object of this invention is to provide a vernier variable condenser which is particularly adapted for use with precision apparatus.

Another object of this invention is to provide a vernier variable condenser in which the rate of capacity change will be substantially uniform throughout the full movement of the variable element.

In vernier variable condensers known in the prior art, considerable trouble was frequently encountered in constructing and keeping the inner rod or electrode concentric with the outermost cylinder, for the reason that any eccentricity of the inner rod electrode or conductor with respect to the outer electrode caused a variation in the rate of capacity change in one revolution of the operating handle.

An object of this invention is to overcome the above mentioned trouble by arranging the inner electrode so that it will not rotate. Therefore, if there is any eccentricity, it will not cause a variation in the rate of capacity change.

This invention will best be understood by referring to the accompanying drawings, in which:

Fig. 1 is a longitudinal section of one embodiment of this invention;

Fig. 1a is a rear elevation of Fig. 1;

Fig. 2 is a longitudinal section of another embodiment of this invention;

Fig. 3 is a still further embodiment of this invention;

Fig. 3a is a cross-section of Fig. 3, the section being taken on lines a—a; and

Fig. 4 is a longitudinal section of still another embodiment of this invention.

Referring now in detail to Figs. 1 and 1a of the drawings, a fixed electrode 1 which is preferably composed of MONEL METAL, INVAR, or some other metal with a very low coefficient of thermal expansion, is supported by two rods 6 to the fixed yoke or plate portion 10. A movable electrode 2 is concentrically arranged within electrode 1 and may be composed of a metal sleeve supported on a quartz rod 3, or, if desired, electrode 2 may be a silver coating upon the quartz rod 3, or it may be formed integral with a guide head 4 which, as shown in the drawings, supports electrode 2 which telescopes over one end of the quartz rod 3. An insulating collar 5 is arranged on the threaded ends of rods 6 for supporting the fixed electrode 1 and is secured thereto by means of a plurality of nuts 6a. A metal sleeve 7 is threaded on the rearmost por-

tion of electrode 1 and serves to retain a spring 9 which keeps the guide head 4 against the spindle of a micrometer head 8, which micrometer head is similar in construction to the ordinary machinist's micrometer, and is described in detail in the Usselman and Franklin application, filed June 27, 1939, S. N. 281,344. The micrometer head is secured to plate 10 which, in turn, is fastened to panel 11 by means of screws 10a. The condenser capacity is varied by moving the barrel of micrometer 8 which, in turn, rotates the spindle 8a and causes guide member 4 to move electrode 2 into electrode 1. Outward movement to decrease the capacity of the condenser is accomplished by means of the expansion of a spring 9 which is interposed between member 7 and a flange 9a located on rod 3. The inner electrode 2 is held concentric to the fixed electrode 1 by guide head 4 at one end and a bearing plate 12 at the rear end of electrode 1. The modification shown by Fig. 2 is somewhat similar to that of Fig. 1, except that the guide rods 6 are dispensed with and a flange-like member 24 is substituted therefor. The fixed metal electrode 21 is secured to flange member 24 by means of an insulating support member 25. The movable electrode 22 is also in the form of a metal sleeve on quartz rod 23 and is so arranged that the support member 25 has a portion of its wall interposed between metallic electrodes 21 and 22, thus increasing the dielectric constant and the active capacity between the electrodes, with the result that the physical dimensions of the condenser is kept at a small size. A plate 26 having a yoke-like portion carries the micrometer head 28 on one side of panel 20, also, the guide 24 on the other side, and is secured to member 24 by means of screws 26a. Member 26 is secured to a panel 20 by means of a plurality of screws 20a. A metal sleeve 29 carries a spring 27 and is secured to electrode 21 by means of screws 29a. Spring 27 is arranged to always force the quartz rod 23 against the spindle of the micrometer through a ball bearing member 30. The embodiment shown by Figs. 3 and 3a is generally similar to that of the construction shown in Fig. 1a, except that the rods 6 are also dispensed with and in their place is substituted a tubular slotted member 36. Member 36 is arranged to guide the movable electrode 32 concentric with the fixed electrode 31 which is composed of any suitable metal having a low coefficient of thermal expansion. Movable electrode 32 is in the form of a metal sleeve or coat-

ing upon a quartz rod 33. Member 32a is in the form of a cylinder which slides in the slotted guide cylinder 36. An insulating flange-like collar 35 is fitted into the slotted cylinder member 36 and carries fixed electrode 31 which is secured by means of a plurality of screws 35a. Extension member 37 is a metallic sleeve threaded on the end of the metallic electrode 31 and carries on its rear-most shouldered portion 37a, a spring member 39. A metal flange 39a surrounds the rear end of insulating rod 33. A micrometer head 38 is fastened to a plate 40 by means of screws 40a to the mounting panel. The foremost end of the metallic sleeve 32 is provided with a rod-like portion 32a having located there-in guide pins 32b, which ride in the slots of member 36. Electrical connection for the condenser is made at terminals 35b and 32b. The electrical connection leads are indicated by arrows connected to members 35b and 32b.

The other form of vernier variable condenser is shown by the sectional view of Fig. 4 and comprises a fixed electrode 41 of a metal having low temperature coefficient of thermal expansion, such as INVAR, and located concentrically therewith is a movable electrode 42 of similar metal. A metal shell 43 serves as a cylindrical piston chamber in which the piston-shape movable elec-

trode 42 works. Member 43 also supports the condenser to the panel 47 and carries an insulator 44 in which fixed electrode 41 is placed. Member 44 may be of fused quartz to increase the capacity of the condenser so that electrodes 41 and 42 may be made much smaller than one in which the dielectric is only that of air. Movable electrode 42 is actuated by the micrometer 48 to increase the condenser capacity and a spring 45 is provided to decrease the condenser capacity.

Although only a few embodiments of this invention has been shown, it is to be distinctly understood that this invention should not be limited to the precise arrangement shown.

15 What is claimed is:

A variable condenser comprising a cylindrical slotted guide member, an insulating member secured to said slotted guide member, a fixed electrode secured to said insulating member, an insulating rod supported by said fixed electrode, a movable electrode secured to said insulating rod, one end of said movable electrode having guide pins to slide in the slot of said slotted guide member, and means to vary the condenser capacity by movement of said movable electrode within said fixed electrode.
